UNITED STATES PATENT OFFICE.

DAVID H. WATTS, OF PHILADELPHIA, PENNSYLVANIA.

DESIGN FOR A TILE.

SPECIFICATION forming part of Design No. 23,772, dated November 6, 1894.

Application filed June 29, 1893. Serial No. 479,171. Term of patent 14 years.

To all whom it may concern:

Be it known that I, DAVID H. WATTS, a citizen of the United States, residing in Philadelphia, Pennsylvania, have invented a certain new and original Design for a Tile, of which the following is a specification.

My design for a tile is fully illustrated in the accompanying drawing, in which the representation is a face view of the tile.

10 The body A of the tile is quadrangular in shape and having at each corner arrow head projections A'.

On the surface of the tile is an ornamentation clearly illustrated in the drawing, hav-

ing a central foliated circle B and extending 15 into each arrow head projection is a foliated rib b. In the center of the circle is a small foliated design c.

I claim—

15 The design for a tile as described and shown 20 in the accompanying drawing.

In testimony whereof I have signed my name to this specification in the presence of two subscribing witnesses.

DAVID H. WATTS.
